BABY EXERCISER

Walter P. Williams and Mildred D. Williams,
Minneapolis, Minn.

Application September 12, 1949, Serial No. 115,154

3 Claims. (Cl. 155—20)

1

This invention relates to exercisers for babies. In the past, there has always been considerable danger connected with baby exercisers. The baby is apt to tip over the platform type of exerciser, and to fall out of the suspension type of exerciser. The purpose of most exercisers is to permit the child to jump up and down, and thus entertain himself; however, the child has, prior to our invention, always been placed in a sitting position, with his legs extended out in front, a situation which makes it very difficult for any child to jump.

It is an object of our invention to provide a novel and improved baby exerciser which positively positions a child therein with his feet and legs permitted to extend substantially straight downwardly to facilitate jumping, and constructed to limit the tipping thereof and prevent overturning to substantially eliminate the danger of the child falling out of the exerciser.

Another object is to provide an exerciser adapted to support the child placed therein in forward position to facilitate jumping, and adapted to also hold the child in the exerciser.

More specifically, it is an object of our invention to provide a baby exerciser having a front and back panel, with only a flexible connection therebetween to prevent pressure against the front panel from swinging the back panel upwardly, and providing a positive positioning of the child within the exerciser and, by providing openings in the bottom portion of the exerciser, permitting the child's legs to extend substantially straight downwardly to facilitate jumping.

These and other objects and advantages of our invention will more fully appear from the following description made in connection with the accompanying drawings wherein like reference characters refer to similar parts throughout the several views, and in which—

Fig. 1 is an elevational view showing the exerciser in operative position and having a child in jumping position therein;

Fig. 2 is a front elevational view of the body portion of the exerciser;

Fig. 3 is a top plan view of the body;

Fig. 4 is a bottom plan view of the body showing the retaining strap in dotted lines;

Fig. 5 is a side elevational view;

Fig. 6 is a fragmentary transverse sectional view taken substantially along the line 6—6 of Fig. 3; and

Fig. 7 is a plan view of the pattern for the material from which the body is formed.

As shown in the accompanying drawings, we 55 10 may be provided, such as the four hanger

2

provide a baby exerciser, the body of which, in the form shown, is made substantially entirely from a single piece of flexible sheet material, such as the canvas sheet 10 illustrated in Fig. 7. This sheet is cut to form a front portion 11, a diminished crotch portion 12, a seat portion 13, and a back portion 14, which has the two side portions 15 integrally formed therewith. A pair of darts 16 are formed at the rear portion of the seat to provide additional fullness and curvature in the body when sewed together to permit the seat to fit the baby and prevent any sliding from side to side.

When the front edge portions 15a of the sides 15 are sewed to the side edge portions 11a of the front portion 11, the leg openings 17 are formed on each side of the crotch 12. The rear portions of these openings 17 are formed by the concavely curved edge portions 13a of the seat 13, as best shown in Figs. 2 through 5, inclusive. Most of the weight of the child within the exerciser is, of course, supported by the seat portion 13 and this concave curvature prevents the rear edges of the leg openings 17 from cutting into the legs of the child. The front portion of the openings 17 is cut away so as to provide ample freedom of movement of the child's legs during the jumping without binding the inner or upper portions of the thighs.

The upper material edge portion of the front portion 11 is doubled back upon itself and a relatively long, stiff, member having a tapered cross-sectional shape, as best shown in Fig. 6, is inserted between the overlapped portion to provide a stiff, 35 flat, member against which the child may lean and which will support the front portion of the exerciser body. The overlapped marginal edge is sewed along the dotted line 11b, as best shown in Fig. 7, to retain the board 18. The marginal edge portion of the back portion 14 is also doubled back upon itself and a rigid member 19 similar to the front member 18 is interposed between the overlapped portions and retained therein as by being sewed along the line 14a. This member 19

40 is somewhat shorter than the member 18, but serves to support the back portion 14 of the body 10. In the form shown, the upper marginal edge portions of the side portions 15 are also doubled back upon themselves, but are not sewed and only 45 provide reinforcement. There is no rigid connection between the front portion 11 and the back portion 14, but only the flexible connection formed by the side portions 15.

Any suitable means for supporting the body 55 10 may be provided, such as the four hanger

straps 20 which are connected at the respective corners thereof as by being looped around the respective end portions of the members 18 and 19. The front portions 11 and 14 have considerable reinforcing, such as the grommets 21 inserted therein to receive the respective straps 20. The upper ends of the straps 20 may be connected to a suitable resilient supporting element, such as the spring 22 shown in Fig. 1, which may be supported from any suitable structure, such as a doorframe in a house, as by the straps 23, or the like.

To adjust the exerciser for operation, the height of the body above the floor should be positioned to permit the child's toes to just touch the floor when in stationary position suspended by the resilient spring 22. When suspended by the spring 22, the exerciser permits the child's legs to extend substantially straight downwardly in order to facilitate his jumping, and the leg openings are designed to permit free movement of the legs without binding or chafing the thighs of the child. The darts 16 provide a curved fullness in the seat 14 which fits the body of the child and prevents side shifting movement within the exerciser. The stiff members 18 and 19 respectively mounted in the front and back portions 11 and 14 form suitable reinforcement for the respective front and back panels, and the front member 18 provides a support against which the child may lean while jumping. The fact that the front member 18 and the back member 19 are connected only by the flexible sides 15 prevents pressure against the front member 18 from tilting the exerciser and raising the back member 19, and substantially eliminates the danger of the child falling out or tipping over the exerciser. In the form shown, a retaining strap 24 has its medial portion sewed to the inside of the front panel 11 and the end portions thereof are adapted to be tied around the body of the child to hold the child against the front panel to provide additional support for extremely young children and to insure a secure attachment of the child to the body of the exerciser.

It will be seen that we have provided a novel and extremely safe child's exerciser, which permits unusual freedom for jumping action and prevents the child from falling out during said jumping. The design of the leg openings 11 permits freedom for leg movement and positively prevents any binding or chafing on the thighs of the child.

It will, of course, be understood that various changes may be made in the form, details, arrangement and proportions of the parts without departing from the scope of our invention.

What we claim is:

1. A child's exerciser having in combination a body, said body comprising a seat portion

shaped to conform to the body of a user and having a pair of leg openings in the lower portion thereof, a back portion connected to the rear portion of said seat and extending upwardly therefrom, a front portion connected to the front of said seat and the upper portion thereof having only flexible connection with the upper portion of said back portion, a pair of relatively stiff reinforcing and supporting members respectively mounted in substantially fixed relation across the upper portions of only the front and back portions and adapted to be connected to suitable supporting means.

2. In a child's exerciser, a body comprising a seat portion having a pair of leg openings formed in the lower portion thereof, a pair of darts formed at the respective rear side portions of said seat and extending inwardly from the respective rear portions of the leg openings to provide a generally curved shape at the rear of said seat to conform to the shape of the child's body and prevent lateral shifting movement thereof when supported therein, an upstanding back panel connected at the rear of said seat and extending upwardly therefrom, a front panel connected at the front of said seat and extending upwardly therefrom in a spaced relation from said back panel, a pair of reinforcing and supporting members respectively mounted in the upper portions of said front and back panels, said members being constructed of relatively stiff material and being adapted to be connected to suitable supporting means, flexible means at the sides of said panels forming the sole means for interconnecting the upper portions thereof, and means connected with said reinforcing and supporting members for normally resiliently supporting said exerciser body in normally spaced relation to the floor.

3. The structure set forth in claim 2 and a retaining strap connected to the front reinforcing and supporting member to surround the child's body and positively hold the child's abdomen against said front member and combine with the curvature of the seat to positively position the child in upright position in the exerciser body.

WALTER F. WILLIAMS,
MILDRED D. WILLIAMS.
